4 Claims. (Cl. 102—8)

This invention relates to a land mine to be dropped from airplanes, moving tanks, or the like. This mine has a safety device which is operative before the ignition setting of the firing pin igniter and has an actuating element which is swivel-mounted, which actuating element completes an idle motion if contacted by detonation waves, especially of a nuclear type, while it actuates the firing pin when contacted in an oblique manner.

Land mines are normally planted by hand with the utmost caution. The mines, the respective igniters and the detonating caps are transported separately to the location where they are to be used and only there, the detonating caps and the igniters are attached to the mine. Each mine is buried at a certain depth and is camouflaged. After this, the safety catch of the igniter is released and the mine will respond to a predetermined pressure.

This pressure may be achieved by a vehicle moving over the mine as well as by detonation waves. Numerous attempts have been made to prevent this latter, unwanted actuation by building the impact elements, i.e. the pressure lid, as small as possible. Another attempt was made to keep the distance between the actuating element and the igniter top so large that by impact the duration of the pressure would not be sufficient to overcome the force of inertia to travel this distance. A further attempt was made to eliminate this disadvantage by using an elastic deformation link between the actuating element and the igniter which link would absorb the first shock and act as a brake. Another possibility is to insert a pneumatic equalizing pressure cushion; this cushion will resist a transient shock, but will break under constant pressure.

It is further known in the art to use an actuating element with a bowl-shaped wall placed in a bowl-shaped bushing. The actuating element is supported by an equally distributed vertical pressure and resists shocks such as encountered in a detonation wave, without putting pressure on the igniter. This structure has shown satisfactory results in the case of small mines (personnel mines). However, in the case of tank mines where the actuating elements cannot be below a certain size because of the structure of the treads, the sudden pressure is of such force that the possible constructive support areas are no longer enough to receive this force.

As a last requirement, it is necessary to lay the mines at such a distance from one another that the detonation of one mine does not influence the remaining mines.

All these structures are satisfactory as long as the detonation waves are of the normal type, spreading with high velocity and disappearing in the same manner. In most cases, the structures known in the art will fail as soon as the mines are touched by a series of quick detonation waves; they fail especially, however, if touched by nuclear explosions which have an extremely high pressure lasting for several seconds.

In the subject structure, the mines are to be dropped from a helicopter or from a moving vehicle and, therefore, it is to be expected that in the known art the actuating element would be released by the impact of the mines falling to the ground and further, that they would be planted irregularly or at short distances from one another which would favor a transmission of detonations;

2

and still further, the mines would come to lie at times upside-down, particularly in soft soil.

Considering the required speed when laying the mines as well as the lack of space in a plane or vehicle, it is necessary that the mines are brought abroad with the detonating caps and igniters already inserted. However, they have to be constructed in such a manner that the igniter is properly secured and that this safety device can be removed in one simple step. As a safety measure during the process of planting the mines, it is further necessary to provide a timing device which ascertains that the mines will respond to pressure only after a predetermined length of time. This timing device must switch on automatically during the process of dropping the mines. Finally, the mine should also meet the requirement for a mine which can either be used as a normal mine or as a mine having a tamper-proof device to prevent it being rendered harmless by the enemy.

To meet this requirement, the subject invention provides an actuating element in the form of a pressure lid characterized by bending resistance, which pressure lid leans against the mine case by interconnecting a hard-elastic inner and an elastic outer ring case, which pressure lid tilts across the surface of the inner ring case during eccentric pressure.

The diameter of the pressure lid, which is constructed with double walls, is approximately the same as the body of the mine so that the explosives will remain at all times beneath the treads of a vehicle. Further, the pressure lid provides a screw cap with a conical opening which, when the safety catch is released, presses against a gliding pressurizer located in the igniter case. The pressurizer transmits the motion received through the firing pin to a concentric running mechanism of known structure, one end of the firing pin being connected to the pressurizer, the other end being connected to the tubular extension of the running mechanism. The tubular extension of the running mechanism is rotated by a flat spiral spring which rotary motion is transmitted to a control case which is rigidly connected with the tubular extension. After a predetermined revolution (safety time), this control case will pull the cylinder block located in an axially movable sliding sleeve downwardly, creating a ring-type cavity. The cavity permits a second cylinder blocking device to yield, which blocking device includes a pair of members which engage a recess in the firing pin and are kept in a blocked position by means of a projection on the igniter case. After removal of the transportation safety plate, the running mechanism is actuated by screwing in the screwing cap. Movement of the cap causes the firing pin to move downwardly whereby a blocking ball positioned in the wall of the tubular extension is actuated by a bobbin mounted on the firing pin which actuates a slider. The slider in turn initiates the rotation of the running mechanism. Mounted on the igniter case is a wrapper cap holding the pressurizer in the igniter by means of a spring. The igniter has a tamperproof device for preventing rendering it harmless. In this arrangement, the wrapper caps are removed and two shearing pins which connect the pressurizer with the igniter case, are sheared off by screwing in a screw cap. When the screw cap is removed, the cylinder block moves upwards exposing the firing pin. By means of this construction, the subject invention meets the above mentioned requirements.

These and various other objects and features will be more clearly understood from a reading of the detailed description of this invention in connection with the drawing in which:

FIG. 1 shows a mine according to one embodiment of the invention in vertical cross section;

FIG. 2 is another exhibit of the outer ring case in cross section;

FIG. 3 is a cross section of the igniter in stationary position;

FIG. 4 is a horizontal cross section of the diameter on the level of the lower cylinder block (taken along the line A-B of FIG. 3);

FIG. 5 is a vertical cross section of the igniter after removal of the transportation safety device with the running mechanism turned on;

FIG. 6 is a vertical cross section of the igniter in actuating position;

FIG. 7 is a vertical cross section of the igniter with a safety device against further handling (without wrapper cap, with shearing pins); and,

FIG. 8 is a vertical cross section of the igniter with sheared off shearing pins in actuating position.

The mine case 1 (FIG. 1) which, for example, is made of a light metal alloy that can be welded, contains explosives 2. Mounted on the mine is a pressure lid 3 which, when receiving pressure, acts on a centrally attached igniter mechanism 4. The pressure lid is of double thickness and has the highest possible bending resistance while using a minimum of weight exertion because of its form. Its diameter approximately equals that of the mine case and is therefore big enough so that a lifting arm is always ready to release the firing pin. The independently suspended outer rim of the pressure lid is supported by elastic and conical ring case 5 which is vulcanized or riveted and which simultaneously protects the inside of the mine against dampness. The diameter of the pressure lid is large enough so that in softer soil, in an upside-down position, enough pressure may be developed to actuate the mine. The center part of pressure lid 3, together with a round or conical plate 6, is supported by a second ring case 8 which is inserted into a ring plate 7. Ring case 8 has an arched surface of hard-elastic material which, in stationary position only, touches in linear contact. Any chosen undulatory form can be used for ring 5. The material used in this ring has been kept somewhat more pliable than that of the inner ring case 8.

When subjected to horizontal pressure from all sides, as caused by nuclear detonation waves, the hard-elastic inner ring case 8 presses against the round or conical plate 6 of pressure lid 3 until said plate is filled out. The ring case 8 may have openings such as holes, slits, etc. (not shown), so that the hard-elastic material can easily yield and mold into plate 6. After that, the support is rigid. Sudden pressures on pressure lid 3, therefore, can be intercepted quickly and within a short distance and no explosion is actuated by detonation waves, for this short distance is not enough to release the igniter 4.

When subjected to pressure on only one side of pressure lid 3, the conical elastic outer ring case 5 yields to the outside and lid 3 tilts across the arched surface of ring case 8. Thereby, a movement perpendicular to the mine axis is accomplished and this motion is translated into movement parallel to the mine axis by the cooperation of a conical cavity member 9 positioned in the screw cap 10 of pressure lid 3 and pressure pin 11. Horizontal movement of member 9 causes vertical movement of pressure pin 11.

In view of the requirements regarding the dropping of these mines, igniter 4 is screwed to the mine case by means of threads 12. Firing pin 13 is kept in a stressed position by means of radially arranged cylinder block 14 which engages the inner wall of the igniter and extends into recess 15 of firing pin 13. A support spring 16 presses pressure pin 11 upwards; the power of the spring is the driving force of the igniter. So that the pressurizer cannot be pushed out of case 4, a wrapper cap 17 is pulled across the igniter and fastened thereto. In its lower part is a concentric, shockproof running mechanism 18 of known art, having a tubular extension 19

which serves as a guide for firing pin flange 20 attached to the lower part of firing pin 13. The upper end 21 of firing pin 13 is parallel to the axis in pressure pin 11. Firing pin flange 20 restrains the firing pin spring 22 which, with its upper end, engages the lower surface of pressure pin 11. The upper part of the tubular extension 19, which projects beyond the running mechanism, is connected solidly with control case 23. Control case 23 supports second cylinder blocks 25 located in a round groove or recess 24 (FIG. 3), blocks 25 are placed radially in sliding sleeve 26. The outer ends of these cylinders are placed in round groove or recess 27 located in the inner wall of the igniter and thus block sliding sleeve 26. This sliding sleeve is arranged so that it can slide along the inner wall of the igniter, secured against rotation by screw 29 located in slit 28 which slit is parallel to the axis.

Pressure pin 11 is of cylindrical shape on the lower part and slides along the inner wall of sliding sleeve 26. Spring 16 rests with its lower end on sliding sleeve 26. In safety position, sliding sleeve 26 is pushed upwards so that it rests against projection 30 in the igniter cylinder wall. In this position, if pressure pin 11 is being pushed downwards, cylinder block 14 of the firing pin cannot yield to the outside; the firing pin is therefore locked to pressure pin 11.

In safety position, a separator piece 31, made preferably of metal, is laid underneath screw cap 10 of pressure lid 3, which separator piece prevents a complete screwing in of the lid 3. The size of this separator piece 31 is measured so that when a tilting of pressure lid 3 occurs, pressure pin 11 of igniter 4 is not being burdened.

Immediately before planting the mine, the separator piece 31 is removed and screw cap 10 of pressure lid 3 is fully screwed in. Pressure pin 11 of the igniter is thereby moved down at a predetermined rate. Since firing pin 13 is in contact with pressure pin 11 through cylinder block 14, the firing pin moves down at the same rate, grazing globe 32 with flange 20 or moving a similar projecting nozzle positioned in the wall of tubular extension 19. This globe or nozzle yields and switches on the running mechanism 18 by actuating slider 37 which acts on agitator 38 of the running mechanism.

Running mechanism 18 is set so that the tubular extension 19 will complete one rotation during a predetermined length of time. This period can be called "safety time" during which the igniter cannot be released or be influenced through pressure on the mine, because the firing pin 13 is locked to the pressure pin 11 by cylinder blocks 14. This period may amount to 5 to 10 minutes. Control case 23, which is connected with tubular extension 19, participates in this rotation so that in the final position (FIG. 4) two opposite vertical grooves 33 which are parallel to the axis are positioned in the control case 23 before block cylinders 25 and sliding sleeve 26. Through the force of supporting spring 16, sliding sleeve 26 strikes down, forming a ring-type cavity 34 (FIG. 6) between the wall of the igniter case and the wall of the pressurizer cylinder. If, after sliding sleeve 26 strikes down, an eccentric force touches the igniter, thereby moving pressure pin 11 downwards, the firing pin-cylinder blocks 14 positioned in cavity 34 are able to yield to the outside, exposing firing pin 13. Under the influence of firing pin spring 22, firing pin 13 will strike and ignite igniter cap 35.

With a minimum variation, the described igniter may be provided with tamperproof means for preventing rendering it harmless. Thus, the igniter may be used as described above or in its normal condition, in which it is simple to render the mine harmless. For this purpose, pressure pin 11 (FIGS. 7 and 8), which was made of aluminum in the above embodiments, preferably should be made of steel. Pressure pin 11 is now pressed against the igniter case by two shearing pins 36. Additionally, wrapper cap 17 has been removed before insertion of the

igniter. When screwing in lid screw cap 10, pressure pin 11 is again pushed downwards, whereby running mechanism 18 is actuated through firing pin flange 20. At the same time, both shearing pins 36 are sheared off. Subsequently, supporting spring 16 presses pressure pin 11 against screw cap 10 of pressure lid 3. As soon as screw cap 10 has been loosened, pressure pin 11 moves upwards until both cylinder blocks 14 of firing pin 13 touch the upper edge of the igniter case (FIG. 8), move outside and release the firing pin.

In summarizing, it is to be noted that among others the following features have been described:

(1) A time-out safety means including a running mechanism 18 having a flat spiral spring, tubular extension 19, slider 37, agitator 38 and flange globe 32 is actuated by the firing pin flange 20 when the safety separator piece 31 is removed and the screw cap 10 is rotated to cause the conical cavity member 9 to engage pressure pin 11 and move the firing pin flange 20 (coupled to the pressure pin 11) downwardly into engagement with flange globe 32.

(2) After the time-out safety means is actuated, the running mechanism 18 rotates tubular extension 19 and the control case 23 until the vertical grooves 33 are aligned with the second cylinder blocks 25 thereby permitting support spring 16 to push sliding sleeve 26 downwardly to create a cavity 34 (FIG. 6) between the periphery of pressure pin 11 and the portion of the igniter means container below projection 30. The mine is now armed and will be actuated by any uneven pressure on the lid 3 which is sufficient to deform the elastic ring 5 and cause the conical cavity member 9, supported in the screw cap 10, to force the pressure pin 11 downwardly until the cylinder blocks 14 are in the plane of the cavity 34. At this point, the firing pin spring 22 overcomes the inertia of the cylinder blocks 14, which normally engage the recess 15 in pin 13 and force the firing pin 13 into engagement with the igniter cap 35, which explodes explosive 2.

Finally, it should be noted that a mine in which the lid does not tilt sideways may be provided with a normal igniter as well as with an igniter having a safety device.

While several embodiments have been shown, it is understood that the concepts thereof could be applied to other embodiments without departing from the spirit and scope of this invention.

What is claimed is:

1. A land mine to be dropped from a moving vehicle, comprising a fuse having a spring loaded pressure pin with a rounded head, timed safety means operable to arm said mine after a predetermined time delay period in response to movement imparted to said pressure pin by pressure on said rounded head, a double walled pressure lid having an outer edge and inner conical surface, a sub-

stantially enclosed mine case, the outer edge of said pressure lid having in contact therewith a supporting elastic ring resting on the mine case, said pressure lid further having a screw cap retainer for adjusting the position of the pressure lid, a conical cavity member loosely enclosing said rounded head of said pressure pin, a further elastic ring having a rounded outer surface located on the mine case, on which outer surface rests said conical area of the pressure lid to afford a mating surface thereby permitting the pressure lid to tilt the conical cavity member relative to the rounded head of the pressure pin to thereby move the pressure pin.

2. A land mine according to claim 1, having firing pin retainer means comprising a firing pin movably positioned within the pressure pin head and forming part of the pressure pin, said firing pin having an annular groove, an expandable retaining collar fitting into said groove, and cylinder locking means located inside the safety means retaining said collar in a position whereby it rests in said groove to hold said firing pin, a control case included in said safety means having therein a sliding sleeve movable out of said cylinder locking means by a change of position of said spring loaded pressure pin to release said retaining collar from the groove in the firing pin.

3. A land mine according to claim 2, characterized in that the firing pin has a needle end carrying a guiding flange, a movable cam located in the opening of the wall of the tubular extension reaching into the path of said guiding flange, a cam operated slider which sets in motion said safety means delay period, said slider mounted for actuation by movement of said cam, and means operable by said screw cap on said pressure lid to move said pressure pin and thus to move said guiding flange into contact with said cam.

4. A land mine according to claim 3, characterized in that said pressure pin is secured by means of two shearing pins positioned with corresponding means to shear off when the screw cap is moved to arm the mine.
